ELECTRIC WAVE GENERATOR

Tyng M. Libby, Seattle, Wash.

Application December 17, 1938, Serial No. 246,358

14 Claims. (Cl. 172—281)

The present invention relates to electric wave generators. In particular, the present invention relates to generators for the generation of electric waves having frequencies in the audible range. Such generators are of use in a voice-frequency carrier telegraph system, for measuring impedances of transmission networks and systems, for modulating the carrier of a radio telegraph transmitter, for loud-speaker testing, in an electric music instrument, and wherever tone frequencies are required.

It is an object of the present invention to construct an electric generator for obtaining various wave-frequencies such as are desirable in the above-mentioned uses.

A further object is the generation of sub-audible-frequencies at comparatively large output power.

Another object is the devising of a simple means for efficiently modulating a radio-frequency at audible and sub-audible rates.

Another object of the present invention is the production of electric waves of desired frequencies by the modulation of a carrier-frequency and the demodulation of the modulated carrier.

A further object of the present invention is the provision of means for keying electric waves in an electrical circuit by keying the biasing circuit of a demodulator.

Another object is the modulation of a super-sonic-frequency by means of a resonant circuit whose reactance is varied at the desired frequency.

It is an object of the present invention to efficiently transform radio-frequency power into audio-frequency power.

Another object is the production of a large number of tone frequencies with the use of a single radio-frequency source.

Another object of the present invention is the provision of a tone generator wherein the instantaneous amplitude of the output is a linear function of a reactive variation in a one-hundred percent modulator.

An object of the present invention is to provide a device for originating a prescribed electric wave form in which the wave form of the output more closely approaches a linear function of the variable reactor than is possible with previous devices.

It is an object of the present invention to provide a carrier-wave modulator having a variable reactor in which the envelope of the modulated carrier is a linear function of the variation of the reactance of said reactor.

Another object is the provision in an electric tone generator, of an electric generator having a variable capacitance, the wave form of the output of the generator being a linear function of the wave form of capacitance variation.

Another object is the provision of a variable inductance in an electric tone generator, the wave form of the output of the generator being a linear function of the inductance variation.

10 It is an object of the present invention to effect a modulation of electric waves in both or either amplitude and frequency, and to control the character of such modulation.

It is an object of the present invention to effect an amplitude modulation of electric waves by varying a carrier-frequency.

Another object of the invention is to provide means for controlling onset and decay of individual tone generators, when keying, by varying the rate of change of the bias on a demodulator.

Another of the objects of the present invention is the production of a device which will produce a complex tone and allow the selection of various rates of onset and decay for various components 25 of the tone.

It is an object of the present invention to effect a frequency modulation of electric waves of audible frequency by varying a carrier-frequency.

These objects are attained in a device such as 30 an audible frequency, or tone, generator by amplitude modulating a high-frequency carrier, the modulator consisting of a network of reactive elements, one of which elements is periodically varied at a desired output frequency. The modulated carrier is then demodulated and the principal component of the output of the demodulator is the desired frequency.

The power output of the demodulator is controlled by means of biasing potentials, and provisions are made for varying the biasing potential 40 at any desired rate, such as to produce desired initial and decay transients in the output circuit of the demodulator. Acoustically this is equivalent to varying the rate of onset and decay.

In the application of these methods to an electric music instrument a common carrier-frequency source may supply a multiplicity of modulating networks each of which is terminated by a separate demodulator and its associated control means. The outputs of the several demodulators may be impressed upon a common amplifier or output system.

50 In an electric music instrument a modulator and its associated control means is provided for each of the notes of the musical scale and each

of the desired harmonics. The outputs of the demodulators for the fundamental tones are connected to a common bus in the output circuit. Likewise all of the demodulators supplying harmonics of the same order are connected to a common bus in the output circuit. A volume control is provided in each bus enabling the relative amplitudes of the fundamentals and harmonics to be controlled as desired.

The simplest form of a modulating network comprises a series inductor and shunt capacitor, or a series capacitor and shunt inductor. In such a network the loss introduced by the network is a function of the variable reactance. There are many alternative forms of networks which will accomplish the modulation of a carrier when at least one of the reactances is periodically varied.

One of the desirable effects in music known as tremolo, comprises periodically varying the amplitude of the component frequencies at the rate of about six cycles per second. In the present device, tremolo is produced by varying the frequency of the carrier supply. The frequency of the audio-frequency output of the demodulator is independent of the frequency and amplitude of the supplied carrier, provided said carrier-frequency and amplitude are constant. Cyclically varying the frequency of the carrier results in corresponding cyclic variations in the amplitude of the audio-frequency output. A periodic variation in the frequency of the carrier at the rate of six periods per second will result in a periodic variation of the audio-frequency amplitude at six periods per second. In this manner tremolo effects are produced.

Another desirable effect in music, known as vibrato, comprises the periodic frequency variation of the component frequencies. In the present disclosure, vibrato is produced by first modulating the audio-frequencies appearing in the common output circuit of the demodulator by means of a fixed carrier-frequency and a balanced modulator. This balanced modulator suppresses the carrier-frequency and transmits the two side-bands. One of the said side-bands is then suppressed by means of a filter, the other of said side-bands being impressed upon a demodulator together with a second carrier-frequency which is varied in frequency at the desired vibrato rate. The output of this second demodulator will then comprise the original tone-frequency varied at the vibrato rate. When several different vibrato frequencies are desired, by the use of a plurality of band filters in the common output circuit of a plurality of demodulators and by associating with each band filter a vibrato producing system as above described, different vibrato rates may be impressed upon various bands of frequencies.

The definitions of some of the terms used herein are as follows:

An element is the smallest entity, or distinct unit, which may be connected into, or disconnected from, an electrical system. The term denotes the electrical representation of the quantities inherent in a physical unit such as an inductance coil, condenser, or resistance unit.

An arm denotes a distinct set of elements electrically isolated from all other conductors in a network except at two points. A series arm is one which conducts the main current in any part of a system in the direction of propagation. A shunt arm is one which diverts a part of the main current from one end of a series

arm (or from one end of a live wire) to a symmetrically located point in a balanced system, or to a ground wire in an unbalanced system.

A branch is one of several parallel paths in a system.

A mesh is a combination of elements, or parts of elements, forming a closed path.

A network is a group of elements inserted in a system for the purpose of satisfying certain transmission requirements, the character, constants, and arrangements of whose elements therefore follow from the necessity of meeting these particular requirements.

A circuit consists of an entire system of interconnected apparatus and conductors designed to transfer electrical energy from one point to another. The term will also be used to describe a part of a complete circuit where proper designation is given, or where the limitations involved are evident. Thus, the input circuit of a network is that part of the entire circuit from which the network derives power.

Linearity in a mathematical concept, may be defined as the condition in which the derivative of the function with respect to the variable is a constant and is independent of the value of the variable. Such linearity is never physically realizable.

By means of the hereinafter disclosed design methods, linearity in attenuation may be obtained over a range in excess of 18 db. with a deviation from linearity of one percent. This linearity may be obtained at attenuation values of from 2 to 20 db. Mechanical constructional limitations may increase the deviation by as much as one-half to five percent or even greater deviation, depending upon the precision of mechanical construction of the variable element. For musical purposes the variation from linearity may be approximately ten percent without detection by the human ear.

The tolerable deviation from linearity depends upon the application of the device; for instance, in the application of this device as a tone generator for laboratory measurements not more than two percent deviation could be tolerated, while on the other hand in its application to a musical instrument deviations from linearity as great as ten percent may be tolerated. The method of designing a linear modulator in this disclosure is not based upon mathematical analyses but rather upon a trial and error method. It has been found that by this method the attenuation of a filter may be made a linear function of a variable reactor in the filter with a deviation not exceeding one percent, over the range of 3 db. to 24 db. attenuation. For the purposes of this disclosure the term linearity shall be construed to mean that the device is linear within the permissible deviations of the particular application of the device.

A wave filter is a selective circuit network designed to pass currents within a continuous band or bands of frequencies, or direct current, and substantially reduce the amplitude of current of undesired frequencies.

Devices for attaining the before mentioned objects and others herein mentioned and apparent, and embodying the before mentioned features, are represented in the accompanying drawings, in which:

Figure 1 is a schematic diagram of a single electric wave generator.

Figures 2, 3, and 4 are modifications of the device shown in Figure 1.

Figure 5 is a schematic diagram of a variable inductor suitable for use as a periodically varying inductance in a modulating network such as shown in Figure 1.

Figure 6 is a view of the rotor of a variable capacitor suitable for use in a modulating network such as illustrated in Figure 1.

Figure 7 is a view of a stator to be associated with the rotor shown in Figure 6.

Figure 8 is a sectional view of the stator and rotor shown in Figures 6 and 7, in their assembled position.

Figure 9 is a schematic diagram of a portion of an electric wave generating system embodying a plurality of generators.

Figure 10 is a schematic showing of an electric wave generator capable of producing amplitude modulation of electric waves.

Figure 11 is a schematic showing of a device for modulating the frequency of electric waves.

Figure 12 is a family of curves showing variation in attenuation as a function of capacitance in a modulating network similar to that shown in Figure 1.

Figure 13 is a graphic representation of the variations in attenuation as a function of capacitance in a modulating network similar to that shown in Figure 1.

Figure 1 is a schematic diagram of an electric wave generator. The rectangle 1 includes a modulating network, a demodulator, a demodulator biasing system, an input circuit, and an output circuit. The input circuit, comprising a transformer 2, couples a carrier-frequency source to the modulating network. The modulating network consists of series elements 3 and 4 and shunt elements 5, 6, and 7. A capacitor 8 allows the free transmission of carrier and audio-frequencies in the modulating network, and blocks the transmission of direct current. A demodulator 9 is connected between the drop side of a series element 4 and a coupling capacitor 10. The coupling capacitor 10 readily transmits the high frequencies in the modulating network while interposing a high reactance to audible-frequencies therein. This capacitor 10 also couples the output of the demodulator to the output circuit. Variable resistors 11, 12, 13 and 14 and rectifier 11a comprise a portion of the demodulator bias control system which with capacitors 15 and 8 control the envelope of the initial and decay transients.

For the purpose of reference, connections with the rectangle 1 are called terminals and numbered. Terminals 20 and 21 constitute the carrier frequency input terminals for the modulating network. Terminals 22 and 23 are terminals for an output circuit. Terminals 24 and 25 are provided for connecting to sources of biasing potential. Terminals 25 and 26 are supplied for connecting a control key in the demodulator biasing system. A control key 27 is connected between the terminals 25 and 26. A source of potential 28 is connected to the terminals 23 and 24 to furnish a blocking bias to the demodulator 9. A further source of potential 29 is connected to terminals 23 and 25 to furnish an operative bias to the demodulator 9. The rectangle 30 represents a source of carrier-frequency which may comprise any well known type of high-frequency oscillator.

In the operation of the device shown in Figure 1: the carrier-frequency from source 30 is transmitted to the demodulator 9 by the modulating network. The amplitude of the carrier im-

pressed upon the demodulator is a function of the attenuation of the modulating network. By periodically varying the capacitance of the capacitor 7, the amplitude of the carrier impressed upon the demodulator is correspondingly periodically varied in amplitude. Such a modulated carrier is known to comprise the carrier-frequency plus side-frequencies. The output frequencies of the demodulator comprise the original input frequency plus the modulating frequency determined by the variable capacitor 7. Of these output frequencies, the frequencies of the same order as those of the carrier are freely transmitted by coupling capacitor 10 while the modulating frequency appears as a voltage across the capacitor 10; hence terminals 22 and 23 may be viewed as the output terminals of an electric wave generator having a frequency the same as that of the variation of capacitance of the capacitor 7. When the key 27 is open, the source of biasing potential 28 renders the demodulator inoperative. Under this condition zero voltage appears at the output terminals.

A demodulator suitable for use in this disclosure is one such that a negative biasing voltage of proper value will make it inoperative. Such a biasing voltage will be called a blocking bias. A biasing voltage of proper value less than the blocking bias will permit the demodulator to function. The output amplitude will be a function of the bias voltage within the operating limits of the demodulator.

When the key 27 is open, the voltage of source 28 is impressed across the demodulator 9 via resistors 11 and 12, the modulator network, and the output circuit. The polarity of source 28 is such that no current from this source will flow through the demodulator. The voltage of source 28 is equal to the blocking bias of the demodulator 9. Since the D. C. resistance of the modulating network and the output circuit is negligible compared to the resistance of the demodulator 9, the voltage of capacitor 8 is the same as the demodulator biasing voltage, under all conditions.

Upon closing the key 27, the D. C. potential sources 28 and 29 produce a current in a clockwise direction in the circuit consisting of these sources in series with key 27 and the resistors 12 and 13. This current produces, in resistor 12, a voltage which is in opposition to the voltage of the source 28, thereby reducing the voltage impressed upon the demodulator 9 and the capacitor 8. This reduction in the voltage impressed upon the capacitor 8 causes it to discharge through resistor 11. The rectifier 11a is poled so that it is non-conducting to the discharge current from the capacitor 8. This discharge of capacitor 8 continues until its voltage is reduced to the difference between the voltages appearing across the resistor 12 and the source 28. The time required for the equalization of the voltage of the capacitor 8 with the difference between the voltages across the resistor 12 and source 28, is a function of the total voltage change of the capacitor 8, the capacitance of the capacitor 8, and the resistance of the resistors 11, 12, and 13. By making the parallel resistance of the resistors 12 and 13 small compared to the resistance of the resistor 11, the rate of change in the bias voltage may be controlled by adjusting the resistance of the resistor 11.

When the final reduced voltage of the capacitor 8 is equal to the bias voltage for efficient operation of the demodulator 9, the closing of the key 27 causes the demodulator bias voltage to de-

crease from the blocking bias value to the demodulator operating value, and thus cause the amplitude of the electric wave in the demodulator output circuit to increase from zero to its maximum value. The rate of this amplitude increase, or the initial transient, may be controlled by adjusting the resistance of the resistor 11. As described above, when the key 27 has been closed for the duration of the initial transient, the biasing voltage, hence, the voltage of the capacitor 8 is equal to the difference between the voltages across the resistor 12 and the source 28. The voltage of the capacitor 15 is zero.

Upon opening the key 27, a transient charging current flows through the capacitor 15, resistors 14, 13, and 12, and the sources 28 and 29 in a clockwise direction. This charging current decreases with time, hence the voltage across the resistor 12 decreases with time, and the difference between the voltage across the resistor 12 and the voltage of the source 28 increases with time, until the capacitor 15 is charged to the sum of the voltages of the sources 28 and 29, whereupon the charging current becomes zero. As the charging current of the capacitor 15 decreases, the voltage across the resistor 12 decreases and the voltage impressed upon the capacitor 8 via the resistor 11 increases, thereby producing a charging current through the capacitor 8 and the rectifier 11a, in an anti-clockwise direction. In this manner, the voltage of the capacitor 8 closely follows the difference between the voltages across the resistor 12 and the source 28. Since this difference of voltage varies inversely with the current through the resistor 12, and since the current through this resistor varies with the capacitance of the capacitor 15 and the resistance of the resistor 14 when the values of the other associated elements are fixed, it follows that the rate of change of the biasing voltage upon opening the key may be controlled by adjusting the values of either the capacitor 15 or the resistor 14, or both. When the voltage of the source 28 is equal to the blocking bias, opening the key 27 decreases the output of the demodulator 9 to zero, and the rate of this decrease, or the decay transient, may be controlled by adjusting the value of capacitor 15 or the value of the resistor 14, or both.

If the rectifier 11a is not employed, the resistor 11 will retard the decay transient. Under this condition, 11 may be made large for obtaining a very gradual initial transient, and then if a sharp decay transient is desired the resistance of resistor 11 should preferably be relatively small. It appears therefore that a large value of resistance in resistor 11 will preclude obtaining a very short decay transient. This difficulty may be eliminated by connecting rectifier 11a in parallel with resistor 11, with the polarity shown in the figure. The function of resistor 11 is unimpaired for the purpose of producing long initial transients, but by virtue of the one-way conductivity of the rectifier 11a, the resistor 11 is effectively short circuited for the decay transient currents produced upon opening the key 27. From the foregoing description it will be seen that the initial transient and the decay transient of the electric wave may be independently controlled.

By selection of appropriate values for the resistors 11, 12, 13, and 14, I have been able to obtain the sharp initial and the long decay transient similar to that produced by striking a bell. By other adjustments of the resistors, a gradual

initial transient simulating that produced by pipe organs has been obtained.

In Figure 1 the variable reactor 7 produced the periodic variation of attenuation in the modulating network. It is to be understood, however, that the reactor 7 may be fixed in value and modulation accomplished by periodically varying the inductance of the inductors 3, or 4, or 5, singly or in combination. The operation of the 10 modulating network and its component elements will be described in more detail hereinafter.

In Figure 1 the inductor 5, while shown as a separate coil, in practice will not have a physical reality but will be obtained by the mutual inductance of inductors 3 and 4. As will be herein-after described, the terminations of the modulating networks may require the inclusion of inductance. The inductance for these terminations may be incorporated in the inductors 3 and 4.

Figure 2 is a modification of a portion of the system shown in Figure 1. In Figure 2 the modulating network differs from that shown in Figure 1, in that in Figure 2 the series arm is a periodically varied inductor 16 and the shunt arm is a fixed capacitor 17. The attenuation of the modulating network is a function of the ratio of series and shunt reactances, hence, as 16 is periodically varied in value, the attenuation of the 25 modulating network is likewise varied periodically which modulates the carrier impressed upon the input terminals 20 and 21. In a manner similar to that described for Figure 1, the modulated carrier is demodulated by demodulator 9, a tone-frequency appearing at the output terminals 22 and 23.

Figure 3 is another modification of Figure 1 and differs from Figure 1 in that one series arm of the modulating network consists of the periodically varied inductor 16 in parallel with a fixed capacitor 18, while the shunt arm of the modulating network is the fixed capacitor 17. The attenuation of the modulating network is periodically varied by variable inductor 16 which thereby modulates the carrier impressed upon input terminals 20 and 21. The demodulator and associated elements are the same as and function as those described in relation to Figure 1.

Figure 4 is still another modification of Figure 1. The modulating network in Figure 4 differs from the modulating network in Figure 1 in that the series arm consists of a resistor 19, and the shunt arm consists of the periodically varied inductor 16 in parallel with the fixed capacitor 18. The attenuation of the network is periodically varied by inductor 16, hence, the carrier impressed upon input terminals 20 and 21 is modulated in accordance with the variations in inductance in the inductor 16. The operation of the demodulator and its associated elements is essentially the same as that described for the demodulator of Figure 1.

While in Figures 1 to 4, inclusive, the demodulator biasing potential is supplied through the circuits connected to the demodulator, it is to be understood that the biasing potential may be impressed upon the demodulator through a suitable choke coil as is commonly known as the parallel feed system.

While there are innumerable networks which will accomplish the desired demodulation in the manner above described, only four have been shown in this disclosure. A general treatment 75 of modulating networks is given hereinafter.

Figure 5 is a schematic diagram of a variable inductor suitable for use as a periodically varying inductance in modulating networks of the types shown in Figs. 2, 3, and 4. A rotor 200 is mounted upon and secured to a rotatable shaft 201, and has poles 202 which carry pole tips 203 of low electrical resistance material. The rotor 200 may be made of conducting or non-conducting material. Inductance coils 204 to 211, inclusive, are mounted about the periphery of rotor 200, the axes of the coils lie on radii of the rotor and are equally spaced in angular displacement. These coils when utilized with high-frequencies are supported preferably by non-conducting material. As shown in Fig. 5, opposite coils are connected in series, as coils 204 and 205 are in series and connected to terminals 214 and 215. The eight coils constitute four generators of the same frequency, any one or all of which may be used as the inductor 16, the terminals of which, 214 to 221, inclusive, are arranged in pairs. The inductance of the coils 204 to 211, inclusive, is periodically varied by rotating the shaft 201, thereby alternately moving conducting pole tips in and out of the magnetic field of the coils. The inductance is a minimum when a pole tip is coaxial with the coils, and the inductance is a maximum when the rotor slot is coaxial with the coil. The frequency of the inductance variation is equal to the product of the number of poles on the rotor and the rate of rotation of the rotor.

Figures 6, 7, and 8 are views of a variable capacitor suitable for use in modulating networks such as illustrated in Figure 1.

Figure 6 is a view of the rotor of the capacitor. The disc 300 which is carried upon a rotatable shaft 301 is preferably made of electrical conducting material such as Wood's metal or other metal suitable for die casting. Tooth electrodes 302 to 305, inclusive, are set in concentric tracks having an integral number of electrodes in each track. The electrodes in a track are equally spaced and have the same dimensions. While the circumferential dimensions of each electrode is here shown to be equal to the circumferential dimensions of the slot between the electrodes, many applications may require a different ratio of electrode to slot dimensions. For maximum capacity variation the depth of the slots should be greater than the slot width.

Figure 7 is a view of the stator of the variable capacitor. The plate 310 is made of a dielectric material suitable for mechanically supporting the groups of conducting electrodes 311 to 314, inclusive. These electrodes are positioned in concentric circles of the same diameters as the corresponding rotor tracks illustrated in Figure 6. The angular displacement of the electrodes corresponds to that of the complementary rotor electrodes. As shown in Figure 7 the peripheral dimensions of the stator electrodes is two-thirds of the peripheral dimensions of the corresponding rotor electrodes. It has been found that these proportions result in a capacitance variation closely approaching a sine wave. For other forms of capacitance variation different dimensions and shapes of electrodes may be employed. The frequency of the capacitance variation is equal to the rate of rotation of the rotor multiplied by the number of rotor electrodes. The capacitance, however, is equal to the capacitance between one rotor electrode and one stator electrode multiplied by the number of such electrode pairs connected in parallel. When the total capacitance of the electrodes on correspond-

ing rotor and stator tracks, exceeds the required capacitance for the duty to be performed, the stator electrodes may be connected in groups so as to provide a number of variable capacitances having the same frequency and a capacitance proportional to the number of electrode pairs connected in a group. In order to obtain a continuously periodic variation in capacitance an integral number of electrodes must be used in each track, hence, the frequencies developed by the concentric tracks on a given rotor must be harmonically related. When stator electrodes are connected in groups it may be desirable to inter-connect diametrically opposite stator electrodes in order to eliminate undesired variations in capacitance due to wobble of the rotor or lack of parallelism between rotor and stator. It will be noted that all of the rotor electrodes are connected electrically, hence all of the capacitances have one common terminal. In practice it has been found desirable to ground this common terminal. When using carrier-frequencies in the order of one-half megacycle or higher, the capacitance between the shaft and its bearings forms a suitable circuit for connecting to the rotor. This eliminates the necessity for rubbing contacts and the resultant noise-frequencies which are ordinarily generated when they are used.

Figure 8 is a sectional view of an assembly of the parts shown in Figures 6 and 7, showing on the left the rotor 300, and shaft 301, and on the right stator mounting plate 310 and stator electrodes 311 to 314, inclusive. For economy in manufacture the rotor may be die cast of metal and the stator may be a moulded phenolic condensation product. In Figures 6, 7, and 8 only a few large electrodes have been shown. By utilizing a disc having a diameter of six inches and one hundred and twenty-eight electrodes in the outer track driven at a speed of 41.2 revolutions per second, I have obtained a frequency variation in capacitance of 5273.6 per second which corresponds to the highest note normally required in a musical instrument. This capacitor had a capacitance of $100 + \sin(2\pi nt)$ micromicrofarads, where n represents the frequency in cycles per second and t represents time in seconds. While in Figures 6, 7, and 8 a single variable capacitor is shown, when a multiplicity of such capacitors are located adjacent to each other they should preferably be electrostatically shielded from one another.

Figure 9 is a schematic diagram of a portion of an electric wave generating system embodying a plurality of individual generators, such as were hereinbefore described, and providing methods and means for combining and controlling different electric wave frequencies for the production of periodic electric waves of any desired shape. Any single valued periodic waveform consists of integrally related frequencies having various amplitudes, the waveform being fixed by the numbers and amplitudes of the integrally related frequencies. It is obvious, therefore, that by providing generators for fundamental and harmonic frequencies, together with means for controlling the amplitude of the individual frequencies, any desired waveform may be obtained.

In Figure 9 the rectangles $A_1/1$ to $A_1/4$, inclusive, and $B_1/1$ to $B_1/4$, inclusive, represent the modulator network demodulator, demodulator biasing system, and associated input and output circuits, represented in the rectangle 1 of Figures 1 to 4, inclusive. The input circuits are energized by a

common carrier-frequency source 30. The rectangle A_{f1} generates a fundamental frequency. The rectangles A_{f2}, A_{f3}, and A_{f4} generate frequencies which are harmonics of A_{f1}, the order of the harmonic being designated by the numeral following the letters A_f. The output from the generator A_{f1} is connected to a common bus 50 and a fundamental bus 51. The output of the generator A_{f2}, which is a second harmonic, is connected to the common bus 50 and to a second harmonic bus 52. The output of the generator A_{f3}, which is a third harmonic, is connected to a third harmonic bus 53. The output of the generator A_{f4}, being a fourth harmonic, is connected to a fourth harmonic bus 54. The output circuits of the group of tone generators B_{f1} to B_{f4}, inclusive, are connected to the fundamental and harmonic buses in a manner similar to the connections thereto of the group of tone generators A_{f1} to A_{f4}, inclusive. The amplitude of the output currents from the buses 51, 52, 53, and 54 are individually controlled by amplitude controls 55, 56, 57, and 58, respectively, while the amplitude of currents from all four buses is regulated by a common amplitude control 59. The output circuit of the common amplitude control 59 is connected to output terminals 60 and 61. The output terminals 60 and 61 may be connected to an amplifier and loud speaker system or to a frequency modulating system, as hereinafter described. Other generators are connected to the fundamental bus 51 and the harmonic buses 52, 53, and 54 in a manner similar to that described for the groups A_f and B_f. Likewise, if desired, additional harmonic generators or sub-harmonic generators may be added to any group. The key terminals 26 of the generators A_{f1} to A_{f4}, inclusive, are connected to contacts on a key A27. The biasing terminals 25 are all bussed in common and connected to the levers of all keys 27.

Upon depressing the key A27 the terminals 25 are connected via the contacts of key A27 to terminals 26 in the generators A_{f1} to A_{f4}, inclusive. The operation of key A27 changes the biasing potential on the demodulator in each of the generators connected to key A27, making the demodulators operative and producing electric waves in the output circuits of each of the associated generators, in the manner described in connection with Figure 1. Similar operation of key B27, changes the biasing potential on the demodulators in the generators B_{f1} to B_{f4}, inclusive, making the demodulators operative and causing electric waves to appear in the output circuits of the associated generators. Other groups may be similarly keyed. Since all of the fundamental sources are connected to the common fundamental bus 51, the amplitude of all fundamental frequencies will be controlled by the resistance 55. Likewise, since all the second harmonic generators are connected to the second harmonic bus 52, the amplitude of all the second harmonics may be regulated by the resistance 56. The third and fourth harmonic amplitudes may likewise be regulated by the resistances 57 and 58, respectively. By means of these independent adjustments of the amplitudes of fundamental frequencies and their harmonics, it is possible to obtain a very large number of wave forms. By means of the common control 59 the amplitude of the resultant electric wave may be regulated. The controls 55 to 58, inclusive, comprise a mixer which may be operated by means of switches with preset values for desired wave forms, and these switches may perform the equivalent functions

and give the same effects obtainable by the organ stops found in the Hammond patent, Number 1,956,350, granted April 24, 1934.

In Figures 1 to 4, inclusive, have been shown individual electric wave generators each supplied by a separate carrier-frequency source, while in Figure 9 a plurality of electric wave generators have been shown as supplied from a single source of carrier-frequency. It is to be understood that while the carrier source has a low impedance, the total impedance in the carrier-frequency supply circuit includes the impedances of the generator input circuits. If only a few generators are supplied by a common carrier-frequency source, the total impedance of the carrier supply circuit may be subject to variations by the generator modulator networks and thus the carrier-frequency may be modulated at its source, and so introduce undesired modulation components in the carrier supplied to other generators. Therefore, when but a few generators are supplied by a common carrier source each generator should be connected to the common carrier source by a resistance pad which will fix the impedance of the carrier supply circuit and avoid undesired modulation components from appearing in the carrier supply circuit. However, when a large number of generators are supplied by a common carrier source the attenuation afforded by the division of power between the generator input circuits will reduce the amplitudes of spurious modulation products which may be produced by the individual modulating networks, and impedance fixing pads are not required.

Figure 10 is a schematic showing of an electric wave generator capable of producing amplitude modulation effects, known in music as tremolo. The rectangle 30 represents a carrier-frequency oscillator of conventional design employing a pentode vacuum tube 31, a tank circuit inductor 32, and an output coupling indicator 33. The frequency generated by this oscillator system is determined by the reactance of inductor 32 together with the associated elements.

An electrical conductor 41 is placed in the field of the inductor 32, which conductor is rotated by a shaft 42, gears 43 and 44, and a prime mover 45. The conductor 41 is rotated at a speed of approximately three revolutions per second. As is well known, the revolution of the conductor 41 will then produce a periodic variation in the inductance of the inductor 32, and thereby produce a periodic variation in the frequency of the oscillator. The frequency of this variation will be twice that of the frequency of rotation of the conductor 41. The effect of this periodic variation in the frequency of the carrier, as noted in the output of the demodulator 9, will be that effect known musically as tremolo. The modulating network and the demodulator, together with the associated keying and control circuits between the input terminals 20 and 21 and the output terminals 22 and 23, are like the elements of the assembly shown in Figure 1 or Figure 2, 3, or 4. The demodulator output terminals 22 and 23 are connected to the input terminals of an amplifier 92 by means of a volume control 59. The output terminals of the amplifier 92 are connected to a loud speaker 93. While in Figure 10 only one modulator, demodulator, and associated keying and control circuits are shown, it is to be understood that a multiplicity of such modulator-demodulator systems may be connected in multiple with the output of the oscillator 30 and the volume control 59, and amplitude modula-

tion produced in all the frequencies generated by the multiplicity of systems.

As described in connection with Figure 1, a constant frequency carrier impressed upon input terminals 20 and 21 is amplitude modulated by the modulating network due to the periodic variation of the reactor 7, which upon demodulation by the rectifier 9, results in electric wave frequencies of constant amplitude in the output circuit of the demodulator. Since the attenuation of the modulator is a function of the frequency of the carrier, the amplitude of the carrier in the output of the modulator may be periodically varied by varying the frequency of the carrier. This may be done as above described by rotating the conductor 41 in the field of the inductor 32. Also, the amplitude of the electric wave in the output of demodulator 9 is proportional to the product of the amplitude of the carrier and the amplitude of side frequencies, and since the amplitude of the carrier is periodically varied it follows that the amplitude of the electric wave in the output circuit of the demodulator will vary at a frequency of twice that of the rotation of the element 41. Hence, rotation of the conductor 41 at a speed of three R. P. S. effects a periodic variation at the rate of six C. P. S. in the amplitude of the electric wave in the output circuit of the demodulator. In order that the percentage of amplitude modulation may be controlled, means for varying the coupling between the inductor 32 and conductor 41 may be employed. The same modulation effect may be accomplished by other means such as by regulating the resistance of the conductor 41.

When frequency modulation is desired, the conductors between the terminals 60 and 60, and between 61 and 91, respectively, may be removed and a frequency modulating system, such as described in connection with Figure 11, may be substituted for the removed conductors.

Figure 11 is a schematic showing of a frequency modulating system. The input terminals 80 and 81 are connected to one winding of a transformer 62 via resistance pad 94. The purpose of the pad 94 in combination with the transformer 62 is to fix the impedance presented to a balanced modulator. The output of transformer 62 is connected to the input of a band-pass filter comprising elements 12, 13, 14, 15, 16, 17, and 18, together with interconnecting conductors. Interposed between the transformer 62 and the band-pass filter is a balanced modulator, comprising elements 63, 66, 67, and 68 which are copper oxide rectifiers such as are ordinarily used in carrier telephone system modulators. A fixed carrier-frequency source 71 is connected to intermediate terminals 69 and 70 of the balanced modulator. A resistance pad 79 is provided for properly terminating the band-pass filter and for interconnecting the filter and terminals 80 and 81 of the balanced demodulator. Interposed between the pad 79 and an output transformer 88, is a balanced demodulator comprising elements 82, 83, 84, and 85 which are copper oxide rectifiers such as are ordinarily used as demodulators in carrier telephone systems.

Connected to intermediate terminals 86 and 87 of the balanced demodulator is a carrier-frequency source 130 similar to the one shown in Figure 10 in rectangle 30. The rectangle 130 represents a carrier-frequency oscillator of conventional design employing a pentode vacuum tube 131, a tank circuit inductor 132, and an output coupling inductor 133. The frequency gen-

erated by this oscillatory system is determined by the reactance of the inductor 132 together with the reactance of the associated elements. An electrical conductor 141 is placed in the field of the inductor 132, which conductor is rotated by a shaft 142, gears 143 and 144, and a prime mover 145. The conductor 141 is rotated at a speed of approximately three revolutions per second. As is well known, the revolutions of the conductor 141 will then produce a periodic variation in the inductance of the inductor 132, and thereby produce a periodic variation in the frequency of the oscillator. The frequency of this variation will be twice that of the frequency of rotation of the conductor 141. This variation may also be affected by periodically varying the capacitance associated with the inductor 132.

When electric waves are impressed upon terminals 63 and 64 of the balanced modulator via terminals 60 and 61, pad 94, and the transformer 62, and a carrier from the source 71 is impressed upon intermediate terminals 69 and 70 of the balanced modulator, the carrier is modulated by said electric waves and for each wave-frequency two side frequencies are produced. One of said side frequencies has a lower frequency than the carrier, and the other side frequency has a higher frequency than the carrier. Those side frequencies having a greater frequency than that of the carrier constitute a sideband commonly referred to as the upper side-band. Likewise, those side frequencies which have a frequency lower than that of the carrier are commonly referred to as the lower side-band. Voltages of both side-bands appear between the primary terminals 63 and 64, while on the other hand the carrier-frequency voltage is suppressed. The elimination of either one or the other of these side-bands is accomplished by the band pass filter which is designed to freely transmit only one of the side-bands. The transmitted side-band after undergoing attenuation by the network pad 79 is impressed upon the primary terminals 80 and 81 of the balanced demodulator. The periodically varied carrier-frequency which is impressed upon the intermediate terminals 86 and 87 of the demodulator has a mean frequency equal to the frequency of the source 71. The action of the demodulator, together with the impressed side-bands and the periodically varied carrier, produces electric waves which are periodically varied in frequency at a rate equal to two times the rotational frequency of element 141. The mean frequency of each of the wave-frequencies, at the output terminals 86 and 87, is identically the same as the wave-frequency, in the input circuit, which produced the side frequency from which any given output wave-frequency was derived. The rate of cyclic variation in the frequency of the output wave is the same as the cyclic variation in the frequency of the carrier, and these cyclic variations have a frequency which is equal to twice the rotational frequency of element 141. The extent of the variations in the carrier-frequency and in the output wave-frequency may be controlled by varying the coupling between rotating element 141 and inductor 132, or by varying the resistance of element 141. While in Figure 11 a source of electric waves and an output amplifier and speaker system have not been shown, it is to be understood that the system of Figure 11 may be introduced between any electric wave source and an associated amplifier for which the system is de-

signed, such for instance its introduction in Figure 10 between terminals 60, 61 and 90, 91.

While in Figure 11 a simple form of balanced modulator and balanced demodulator has been shown, any one of a large number of such devices may be utilized in the present application. The particular type of balanced modulator and demodulator shown herein has been completely disclosed and its operation described in the "Bell Laboratories Record" of March 1937, Vol. XV, No. 7, published by Bell Telephone Laboratories, Incorporated, 463 West Street, New York city, N. Y. In Figure 11 the band pass filter shown is for a simple crystal filter but any one of a large number of types may be used in this application. For a description of filters suitable for this application reference is made to the "Bell System Technical Journal" of October 1937, Vol. XVI, No. 4, published by the American Telephone and Telegraph Company, 195 Broadway, New York city, N. Y.

Figure 12 is a family of curves showing variation in attenuation as a function of capacitance in a modulating network similar to that shown in Figure 1. These curves are for "m" derived types of modulating networks, wherein the prototype network is a constant "k" filter. Attenuation versus capacitance for the prototype filter is shown by the curve labeled "m equals 1.0."

Figure 13 is a graphic representation of the variations in attenuation as a function of capacitance in a modulating network similar to that shown in Figure 1. The curve A shows the variations in attenuation as a function of the capacitance when the shunt resistance ϵ in Figure 1 is a zero. Curve B shows the variation in attenuation as a function of capacitance when the resistance ϵ , in Figure 1 is 200 ohms. Curve C shows the variation in attenuation as a function of the capacitance when the resistance ϵ , in Figure 1 is 200 ohms and the terminating impedances each have a magnitude of 937 ohms and a positive angle of 33 degrees. The curve C is for the total insertion loss of the modulating network, and illustrates the degree and range of linearity which may be obtained in a modulating network such as shown in Figure 1.

In the application of modulating networks, such as shown in the drawings, to the production of electric waves, the total insertion loss of the network should be a linear function of the periodically varied reactance in the network.

When the total insertion loss of the modulating network is a linear function of its variable reactance, the wave form of the output is the same as the wave form of the variable reactance. When the total insertion loss is a linear function of the capacitance of a periodically varying condenser in the network, the envelope of the output will be the same in form and period as that of the capacitance variation. Thus, if the capacitance varies sinusoidally the carrier is sinusoidally modulated, and by utilizing a linear demodulator, a pure sine wave of current having the same frequency as the sinusoidally varied capacitance will be obtained in the demodulator output circuit.

A modulating network in which the total insertion loss of the network is a linear function of a periodically varied inductance, capacitance, or resistance will be referred to as a linear modulating network.

A modulating network should not dissipate more than a few percent of the power delivered to it; the percent modulation should be controllable

between zero and 100%, it should consist of a minimum number of physically realizable elements which are simple and inexpensive; and the characteristics of the network should be stable. These requirements may be met by a single section wave filter having a periodically varying reactor as one of its elements. In the following discussion, the design of such a filter when used as a linear modulating network having a periodically varying capacitance, will be presented.

The simplest form of a single section wave filter consists of a series impedance Z_1 and a shunt impedance Z_2 . The freely transmitting band of such a filter is known to occur for the values of Z_1 and Z_2 such that

$$O > Z_1/4Z_2 > -1 \quad (1)$$

For all other values of $Z_1/4Z_2$ the filter will attenuate. In Equation 1 it is evident that the transition from free transmission to attenuation occurs for the values:

$$(a) \quad Z_1/4Z_2 = 0$$

$$(b) \quad Z_1/4Z_2 = -1 \quad (2)$$

The attenuation of the filter may be varied by varying the value of Z_1 or Z_2 or the ratio Z_1/Z_2 in the regions shown in Equation 2.

The condition *a* is satisfied when:

- (1) Z_1 is zero when Z_2 is finite.
- (2) Z_1 is finite when Z_2 is infinite.
- (3) Z_1 is zero and Z_2 is infinite simultaneously.

The condition *b* in Equation 2 is satisfied when Z_1 and Z_2 are both finite but opposite in sign. This condition can be satisfied with a much simpler network than that required to satisfy condition *a* above.

The requirements of *b* are satisfied by a simple symmetrical low-pass or high-pass wave filter. The attenuation of such a filter is known to be

$$A + iB = 2 \sinh^{-1} \sqrt{Z_1/4Z_2} \quad (3)$$

where *A* is the attenuation constant and *B* is the phase constant.

The total insertion loss of such a network, in addition to the attenuation above defined, includes the reflection losses between the iterative impedances of the network and the terminating impedances, plus the interaction loss.

The total insertion loss for a symmetrical filter having equal sending end and receiving end terminating impedances may be expressed in the form

$$L_T = A + 40 \log_{10} \left| \frac{Z_R + Z_K}{\sqrt{4Z_R Z_K}} \right| + 20 \log_{10} \left| 1 - \left(\frac{Z_R - Z_K}{Z_R + Z_K} \right)^2 \cdot e^{-2(A+iB)} \right| \quad (4)$$

where *A* and *B* are as defined in Equation 3, Z_R is the sending and receiving end impedance, and Z_K is the image impedance of the network.

It is apparent from Equation 4 that no practical analytical solution exists for determining the values of Z_1 and Z_2 for a desired loss characteristic. It is therefore necessary to plot a family of curves for loss as a function of the parameters, and from such curves, the necessary types and values of impedance elements may be selected to provide a given loss characteristic. Also, if design formulae could be derived and were used, there would be no assurance that the analytically derived values of Z_1 and Z_2 , to meet a specified set of conditions, would be physically realizable, hence, empirical methods would be required to supplement any analytical design formulae.

As an illustration of a method which I have used for designing a linear modulating network, the following example is given.

In the generation of tone-frequencies in the musical scale, frequencies as great or greater than 5273.6 cycles per second are required. If this frequency is to be obtained in accordance with the methods of this disclosure, utilizing a variable condenser in a linear modulating network, the condenser must have a frequency of capacitance variation of 5273.6 cycles per second. This condenser may consist of a stator and a rotor each having 128 teeth or electrodes, the rotor being driven at a speed of 41.2 revolutions per second.

When the rotor and the stator are parallel disks having electrode tracks of mean diameter d , gap clearance t , radial dimension r , with the circumferential dimensions of each electrode equal to the circumferential dimensions of the slots between adjacent electrodes, air dielectric, and all dimensions in inches, the capacitance may be expressed in micromicrofarads as

$$C = \frac{1.113dr}{8t} \quad (5)$$

In such a condenser, the variation in capacitance between the rotor and stator is very nearly sinusoidal when the tooth and slot peripheral widths are equal on one member and on the second member the tooth width is one-half the slot width of that of the first member. A condenser of this type having a rotor diameter of six inches and a radial dimension of three-eighths of an inch was constructed and its capacitance was found to be $100 + 25 \sin 2\pi nt$ micromicrofarads, where n is the number of cycles per second obtained by multiplying the revolutions per second by the number of rotor teeth, and where t is time in seconds.

Using such a condenser as the shunt element in a lowpass constant "k" type wave filter, at the cutoff point

$$\frac{Z_1}{4Z_2} = -\frac{\omega^2 L_0 C_0}{4} = -1 \quad (6)$$

wherein ω is 2π times the impressed frequency, L_0 is the inductance of the series element, and C_0 is the minimum capacitance of the shunt element. Let the value of $C_0 = 150 \times 10^{-12}$ farads and let $L_0 = 2 \times 10^{-3}$ henries, then at the cutoff point

$$\frac{Z_1}{4Z_2} = -1 = \frac{3\omega^2 \times 10^{-12}}{4}$$

from which the frequency of the impressed carrier is found to be 581,098 cycles per second and $\omega = 3,651,480$. Introducing this value of ω , together with the value of L_0 , Equation 6, gives

$$\frac{Z_1}{4Z_2} = -\frac{2}{300} C_0$$

Substituting this value of $Z_1/4Z_2$ in Equation 3 results in

$$A + jB = 2 \sinh^{-1} \sqrt{\frac{2C_0}{300}} - 2 \cosh^{-1} \sqrt{\frac{2C_0}{300}} \quad (7)$$

By plotting values of attenuation versus C_0 , as calculated from Equation 7, the attenuation is found to be far from linear (see curve $m=1.0$ in Figure 12). However, by inserting a small fixed resistance in series with the element L_0 , the attenuation characteristic may be made linear over a portion of its length. This may be shown as follows:

Let the quotient of the inserted resistance R

and the reactance L_0 of the coil be designated by *d*, i. e.,

$$\frac{R}{\omega L_0} = d$$

then $j\omega L_0 = (d + j1) \omega L_0$ and the attenuation, from Equation 7 becomes

$$A + jB = 2 \sinh^{-1} \sqrt{\frac{(1 - jd) 2C_0}{300}} \quad (8)$$

Wherein $j = \sqrt{-1}$. In (8) using the values of $2C_0/300$ which were used in Equation 7, the points for new curves may be calculated for several values of d . While such curves are not herein shown, they have been plotted, and for the present example it was found that for $d=0.2$, the attenuation characteristic does not deviate more than 4.5% from absolute linearity over the range of 3 db. to 12 db. attenuation.

It can be similarly shown that the same results can be obtained by inserting resistance in the shunt element.

For many applications, the attenuation characteristic of the type "k" filter used in the foregoing example would be satisfactory. The networks shown in Figure 2 and 3 may be designed in this manner. However, when larger variations of attenuation with lower minimum values are required, the "m" derived types of filters are more satisfactory than the prototype.

Using the foregoing "k" type filter as the prototype, the mid series "m" derived types have been determined and their attenuation characteristics versus capacitance has been computed. These characteristics are shown in Figure 12.

The method of designing "m" derived types of filters is fully disclosed in such publications as "Transmission Circuits For Telephonic Communications," a book by K. S. Johnson published 1925 by D. Van Nostrand Company, Eight Warren Street, New York, N. Y., and "Transmission Networks and Filters," a book by T. E. Shea published 1929 by D. Van Nostrand Company, Incorporated, 250 Fourth Avenue, New York, N. Y.

In Figure 12, the attenuation characteristics for the "m" derived types have double flexures, these flexures occurring at higher values of attenuation as "m" approaches unity. The portion of the characteristic lying below the double flexure may be made to closely approach linearity by inserting resistance in either or both the series or shunt arms of the filter.

In Figure 13, the attenuation characteristic for the "m" derived filter wherein $m=0.6$ is shown by a curve A for the condition of zero resistance and by the curve B for 200 ohms inserted, in the shunt arm. A different value of resistance which would produce a much closer approach to linearity could be inserted, but 200 ohms was selected in order to obtain a linear characteristic for the total insertion loss, as explained later.

In linear modulators of the type considered, the image impedance Z_k is a function of the variable reactor and therefore varies with the attenuation. The terminating impedances Z_R remain fixed. In the present example, both Z_k and $(A+B)$ vary with the capacitance, and it is evident from Equation 4 that both the reflection and the interaction losses must likewise vary with the capacitance.

Note, in Equation 4, that when Z_R and Z_k are closely alike in both magnitude and angle, the reflection and interaction losses become very

small. Also, the interaction loss becomes smaller as A increases. That is, the interaction loss is of importance only when A is small. However, when A is small, the interaction loss is a function of B , and in the linear modulator B varies over a range of about two radians.

Several values of terminating impedances, having values approximating Z_k for the low attenuation region, should be inserted in Equation 4, and the magnitudes of the reflection and interaction losses thus determined. A value of Z_k must be found for which these losses are small over the operating range of the capacitance, or for which the sum of these losses is a linear function of the variable capacitance.

In the present example, a satisfactory value for the magnitude of Z_R was found to be equal to the magnitude of Z_k when $C=90$ mmf. This is the value of C at which $A=0$ for the "k" prototype filter.

The optimum value of the angle for Z_R is the mean between the angles of Z_k for $C=90$ mmf. and $C=85$ mmf. The compromise value selected for Z_k is $937 \angle 33^\circ$. This value of terminating impedance results in a total insertion loss characteristic which does not deviate from linearity by more than 0.1 db. between 3 db. and 24 db.

The positive reactance required for the terminating impedances may be included in the inductance of the series arms of the filter, thus avoiding the necessity of providing additional coils for this purpose. Likewise, the inductance in the shunt arm of the modulator may be derived from the mutual inductance of the coils in the series arm. In this manner a single center-tapped coil and a suitable variable condenser constitute the necessary reactance elements for the linear modulator and its terminations. In a manner similar to the foregoing, it can be shown that the periodically varying reactor could be an inductance rather than a capacitance.

The design problem wherein a variable inductance is used in the linear modulator is simplified by the fact that the reactance of a coil is a linear function of its inductance, whereas the reactance of a condenser is not a linear function of its capacitance.

Since the reactance of an inductor is a linear function of its inductance, the ratio of Z_1/Z_2 , which includes a variable inductance, is likewise a linear function of the variable inductance. Families of curves showing the attenuation characteristics of a large number of wave filters have been published in the references cited. Attenuation characteristics approximating linearity may be selected from these curves, and by trial, the appropriate value of resistance to be inserted for producing linearity may be determined by the data and formulae set forth herein.

The amplitude modulating network described above is distinguished from other modulating networks in that its dissipation is low, its modulation factor is high and its total insertion loss is a linear function of its variable reactor. Such a network is shown in Figure 1.

Having thus described my invention, I claim:

1. In an electric frequency modulator: a balanced modulator having an input circuit and an output circuit, means for impressing upon the input of said modulator a constant frequency carrier wave, a wave filter connected to said output circuit and adapted to transmit but one side-band from said modulator, a balanced demodulator having an output circuit and an in-

put circuit adapted to receive the output of said wave filter, and means for impressing upon said demodulator a second carrier wave having a periodically varied frequency; whereby electric wave frequencies impressed upon said input circuit will appear in said output circuit modulated in frequency at a frequency equal to the frequency variation of said periodically varied carrier.

10. An electric wave generator, comprising: a source of carrier-frequency, a demodulator having an output circuit, a modulating filter connecting said source to said demodulator, the characteristics of the elements of said filter being such that it operates on its cutoff characteristic with respect to the carrier-frequency from said source, said filter having therein a variable reactor, and means for cyclically varying the reactance of said reactor for the purpose of modulating said carrier-frequency and of producing a modulating frequency in the output of said demodulator.

25. An electric wave generator, comprising: a source of carrier-frequency, a demodulator having an output circuit, a modulating filter connecting said source to said demodulator, the characteristics of the elements of said generator being such that the filter operates on its cutoff characteristic with respect to the carrier-frequency from said source, said filter having therein a variable reactor, and means for cyclically varying the reactance of said reactor for the purpose of modulating said carrier and of producing a modulating frequency in the output of said demodulator.

30. An electric wave generator, comprising: a source of carrier-frequency, a demodulator having an output circuit, a modulating filter connecting said source to said demodulator, the characteristics of the elements of said generator being such that the filter operates on its cutoff characteristic with respect to the carrier-frequency from said source, said filter having therein a variable reactor and a resistor, said resistor being of a value that the attenuation of said filter to the carrier-frequency from said source will vary linearly with respect to variations of the reactance of said reactor, and means for cyclically varying the reactance of said reactor for the purpose of modulating said carrier and of producing in the output of said demodulator a wave form linear with respect to the variations in reactance of said reactor.

35. An electric wave generator, comprising: a source of carrier-frequency, a demodulator having an output circuit, a modulating filter connecting said source to said demodulator, the characteristics of the elements of said generator being such that said filter operates on its cutoff characteristic with respect to the carrier-frequency from said source, said filter having therein a variable reactor and a resistor, said resistor being of a value that the attenuation of said filter to the carrier-frequency from said source will vary linearly with respect to variations of the reactance of said reactor, and means for varying the reactance of said reactor linearly with respect to a desired wave form for the purpose of modulating said carrier and of producing in the output of said demodulator the desired wave form.

40. An electric wave generator, comprising: a source of carrier-frequency, a demodulator having an output circuit and a biasing circuit, a modulating filter connecting said source to said

demodulator, the characteristics of the elements of said filter being such that it operates on its cutoff characteristic with respect to the carrier-frequency from said source, said filter having therein a variable reactor, means for cyclically varying the reactance of said reactor for the purpose of modulating said carrier frequency and of producing a modulating frequency in the output of said demodulator, and means for keying said biasing circuit.

7. An electric wave generator having a source of modulated carrier-frequency; and a demodulator having an input side connected to said source, an output circuit in which is produced through the action of said demodulator the modulating frequency of said carrier-frequency, a biasing circuit, and means for keying said biasing circuit to control in said output circuit the output of said demodulator.

8. An electric wave generator having means for controlling the output of said generator, comprising a source of modulated carrier-frequency; and connected to said source, a demodulator having an input side connected to said source, an output circuit in which is produced through the action of said demodulator the modulating frequency of said carrier-frequency, and a biasing circuit, means in said biasing circuit for supplying a bias for biasing said demodulator, and means for varying said bias whereby in said output circuit the amplitude of the output of said demodulator is varied.

9. An electric wave generator, comprising: a source of carrier-frequency, a demodulator having an output circuit, a modulating filter connecting said source to said demodulator, the characteristic of the elements of said filter being such that it operates on its cutoff characteristic with respect to the carrier-frequency from said source, said filter having therein a variable reactor, and means for cyclically varying the reactance of said reactor for the purpose of modulating the carrier-frequency and of producing a modulating frequency in the output of said demodulator, means for biasing said demodulator and means for varying said bias to control the amplitude in the output of the demodulator.

10. An electric wave generator comprising: a source of modulated carrier-frequency, a demodulator connected to said source and having a biasing circuit, means for keying said circuit, and in said circuit a variable impedance for controlling the amplitude of the output of said demodulator.

11. An electric wave generator, comprising:

a source of carrier-frequency, a demodulator having an output circuit, a modulating filter connecting said source to said demodulator, the characteristics of the elements of said filter being such that it operates on its cutoff characteristic with respect to the carrier-frequency from said source, said filter having therein a variable reactor, and means for cyclically varying the reactance of said reactor for the purpose of

10 modulating said carrier-frequency and of producing a modulating-frequency in the output of said demodulator, and means for cyclically varying the frequency of the carrier produced by said source whereby the output of said demodulator will cyclically vary in amplitude.

12. In an electric wave generator employing a modulated carrier-frequency: a demodulator having an output and an input adapted to have impressed thereon a modulated carrier-frequency, a source of biasing voltage for said demodulator, and means connecting said demodulator and said source for impressing said biasing voltage upon said demodulator and for increasing and decreasing said impressed voltage.

20 13. In an electric wave generator employing a modulated carrier-frequency: a demodulator having an output and an input adapted to have impressed thereon a modulated carrier-frequency, a source of biasing voltage for said demodulator, and means connecting said demodulator and said source for impressing said biasing voltage upon said demodulator and for increasing and decreasing said impressed voltage.

25 14. In an electric wave generator employing a modulated carrier-frequency: a demodulator having an output and an input adapted to have impressed thereon a modulated carrier-frequency, a source of biasing voltage for said demodulator, and means connecting said demodulator and said source for impressing said biasing voltage upon said demodulator and for increasing and decreasing said impressed voltage, said means including a rectifier in parallel with an impedance for differentially controlling the rate of increase and decrease of said impressed biasing voltage whereby the output amplitude of the demodulator may be increased and decreased at a differential rate.

30 15. In an electric wave generator employing a modulated carrier-frequency: a demodulator having an output and an input adapted to have impressed thereon a modulated carrier-frequency, a source of biasing voltage for said demodulator, and means connecting said demodulator and said source for impressing said biasing voltage upon said demodulator and for increasing and decreasing said impressed voltage, said means including a rectifier in parallel with an impedance for differentially controlling the rate of increase and decrease of said impressed biasing voltage whereby the output amplitude of the demodulator may be increased and decreased at a differential rate.

35 16. In an electric frequency-modulator: a balanced modulator having an input and an output circuit, means for impressing upon the input of said modulator a constant frequency carrier-wave, a wave filter connected to said output and adapted to transmit but one side-band from said modulator, a balanced demodulator having an output circuit and an input circuit adapted to receive the output of said wave filter, and means for impressing upon said demodulator a second carrier-wave having a varied frequency; whereby electric wave-frequencies impressed upon said input circuit will appear in said output circuit modulated in frequency at a frequency equal to the frequency variation of said varied carrier.
